COVER MOUNTING AND LOCKING MEANS
FOR TANKSFrank A. Holby, Riverside, Conn., assignor to The
William F. Kenny Company, New York, N. Y.,
a corporation of New York

Application August 10, 1939, Serial No. 289,486

2 Claims. (Cl. 292—336)

This invention relates to cover mounting and locking means for tanks, such as the tanks of tank trucks, for example, and has as its object to provide such means facilitating the locking operation. To this end, I provide means for holding the locking means in operated position when the cover is opened, the holding means being automatically released as the cover moves to closed position.

A practical and illustrative embodiment of the invention is shown in the accompanying drawing with reference to which I shall proceed with the description. In the drawing:

Figure 1 is a plan view of mounting and locking means in accordance with the invention.

Figure 2 is a section substantially on line 2—2 of Figure 1, and

Figure 3 is a view similar to that of Figure 2, but showing the parts in different relation.

Referring to the drawing, reference numeral 10 designates the shell of a tank and reference numeral 11 a top opening in one of the tank compartments. A plate 12 has a peripheral flange 13 conformed to the margins of the opening 11 and secured to the shell by rivets. Plate 12 has a circular central opening 13'.

On the forward side of opening 13', an upstanding member 14 is fixed to plate 12 and supports a bearing 15 whose axis is normal to the central vertical longitudinal plane of the tank. Directly opposite upright 14, a catch member or keeper 16 is secured to plate 12, this catch member having a lower surface 17 sloped downwardly away from opening 13 and a cam surface 18 which is sloped upwardly and away from opening 13.

An arm 19 is pivoted on a pin 20 in bearing 15 for swinging movements between the full line and horizontal position shown in Figure 2 and the dotted line position indicated in the same figure. Arm 19 is constituted by side bars 21 and 22 connected by a web 23. The free extremities of bars 21 and 22 are deflected away from each other and are pierced for the reception of a pin 24 parallel to pin 20.

A cover 25 for opening 13 is provided with a central cylindrical socket 26 in which are received upper and lower bushings 27 and 28, these being conformed to mate with the spherical surface of a ball 29 which has fixed thereto a threaded stem 30. Bushing 27 is threaded into socket 26 and is retained in adjusted position, wherein ball 29 is frictionally engaged by the bushings, by a set screw 31. Bushing 27 has an opening 32 through which stem 30 is passed with extra clearance. Stem 30 is threaded in an opening in web

23 and locked by a nut 33 with the cover 25 spaced from arm 19 sufficiently so that the cover has the possibility of universal tilting relative to stem 30.

A bell crank lever 34 is pivoted at its angle centrally of pin 24. One portion 35 of lever 34 extends above and along arm 19, as shown in Figure 2, the other portion 36 of the lever extending downwardly and carrying, between its two side webs 37 and 38, a pin 39, parallel to pin 24, on which is mounted a roller 40 for cooperation with catch member 16. Portion 36 has a web 41 connecting webs 37 and 38, and having an opening 42 formed therein presenting a straight bottom edge 43.

15 A latch 44 is mounted in longitudinally extending relation on web 23, the head end of the latch projecting through opening 42 and being provided with a shoulder 45. At its other end, latch 44 has a perforation in which is engaged a bolt 46 which is secured in web 23. The bolt is loosely received in the perforation so that pivoting of the latch is permitted. A compression spring 47 is disposed between the head of the bolt and the latch and tends to depress the latter.

In Figures 1 and 2, the roller 40 is engaged with surface 17 of keeper 16. The roller is forced against surface 17 by a spring 48 which has end coils surrounding pin 24 between bars 30 21 and 22 and lever 34, the spring having a bale portion engaged over lever portion 35 and tending to move the latter toward arm 19. With the parts in this relation, the cover is held securely under this condition the nose of latch 44 rests on the top side of keeper 16. To open the cover, an upward pull is exerted on lever portion 35, so that roller 40 moves out from under keeper 16. As arm 19 is swung upwardly, latch 44 is forced 40 downwardly by spring 47 so that shoulder 45 engages web 41 below edge 43, thus holding the locking means in the operated condition shown in Figure 3. With the cover fully opened, arm 19 is supported just past the vertical, as indicated in dotted lines in Figure 2. Due to the

rather delicate balance of the arm in this position, any movement of the truck will throw it off balance, so that the cover will return to closed position. In returning to this position, roller 40 strikes surface 18 of the keeper, so that lever 34 is swung slightly in a counter-clockwise direction about pin 24, thus releasing the frictional engagement between shoulder 45 and the face of web 41. The nose of latch 44 then strikes the top of keeper 16 and web 41 moves

below shoulder 45 of the arrested latch, so that the spring 48 is enabled to swing lever 34 in a clockwise direction to engage roller 40 with surface 17. This engagement would be effected by the weight of lever portion 35 in the absence of spring 48, but the provision of the spring is desirable as a steadyng factor.

Proper seating of the cover is assured by its universal tiltability relation to arm 19 as provided by the ball and socket connection.

It will be understood that the invention is susceptible of varied embodiment and that, accordingly, I do not limit myself to details of form and arrangement of parts, except as in the following claims.

I claim:

1. In combination, a member pivoted at one end, a fixed keeper at the free end of said member having an angular head, means on the free end of said member engageable under the head of said keeper and releasable therefrom, said means being swingable on an axis parallel to the pivoting axis of said member, and a latch carried by said member and engaging and holding said swingable means in withdrawn position

when the latter is released from the keeper, said latch having a portion positioned to strike the top of the keeper head to release the latch from said swingable means as said member swings toward said keeper.

2. In combination a member pivoted at one end, a fixed keeper at the free end of said member having an angular head, means on the free end of said member engageable under the head of said keeper and releasable therefrom, said means being swingable on an axis parallel to the pivoting axis of said member, and a latch carried by said member and engaging and holding said swingable means in withdrawn position when the latter is released from the keeper, said latch having a portion positioned to strike the top of the keeper head to release the latch from said swingable means as said member swings toward said keeper, said head having a cam face struck by said swingable means as said member swings toward said keeper whereby to move said swingable means in its direction of release so as to loosen its engagement with the latch before the latter strikes the keeper.
